CLAIM

The ornamental design for a receiver for remote controller, as shown and described.

DESCRIPTION

FIG. 1 is a perspective view of a remote controller showing my new design;

FIG. 2 is a front elevational view thereof;

FIG. 3 is a rear elevational view thereof;

FIG. 4 is a top plan view thereof;

FIG. 5 is a reference bottom plan view thereof; and,

FIG. 6 is a right side elevational view thereof, a left side elevational view thereof being a mirror image.

The broken lines are for illustrative purpose only and forms no part of the claimed design.
